UNITED STATES PATENT OFFICE.

WILLIAM W. HUNTLEY, OF SILVER CREEK, NEW YORK, ASSIGNOR, BY MESNE ASSIGNMENTS, TO HUNTLEY, CRANSON & HAMMOND, OF SAME PLACE.

DEVICE FOR OPERATING THE SHAKING-SHOES OF GRAIN-SCOURERS, &c.

SPECIFICATION forming part of Letters Patent No. 436,581, dated September 16, 1890.

Application filed June 4, 1888. Serial No. 275,935. (No model.)

To all whom it may concern:

Be it known that I, WILLIAM W. HUNTLEY, of Silver Creek, in the county of Chautauqua and State of New York, have invented a new 5 and useful Improvement in Devices for Operating the Shaking-Shoes of Grain-Scourers, &c., of which the following is a specification.

This invention relates to a device for transmitting motion, and is more especially designed for use in grain-scourers, grain-separators, and analogous machines in which a shaking-shoe is employed which is operated from the main driving-shaft.

The object of my invention is to provide a 15 simple connection whereby the shaking-shoe is operated directly from the main shaft.

The invention consists of the improvements which will be hereinafter fully set forth, and pointed out in the claim.

20 In the accompanying drawings, Figure 1 is a side elevation of a grain-scourer provided with my improved shoe-actuating device. Fig. 2 is a vertical longitudinal section of a portion of the vibrating shoe, showing the 25 plate to which the end of the connecting-strap is secured. Fig. 3 is a top plan view of said plate. Fig. 4 is an enlarged side elevation of the actuating device. Fig. 5 is a cross-section of the oscillating quadrant and its supporting-bracket. Fig. 6 is a cross-section of the eccentric and a portion of the connecting-strap.

Like letters of reference refer to like parts in the several figures.

35 A represents the stationary frame of a grain-scourer.

B is the casing inclosing the revolving scouring drum or cylinder, and C is the wind-trunk.

40 d is the horizontal driving-shaft arranged lengthwise of the machine and upon which the scouring-drum is mounted. The driving-shaft d is journaled in bearings arranged in the end frames of the machine.

45 E represents the shaking-shoe arranged above the casing B and supported upon flexible arms or bars e, secured with their lower ends to the frame A. The shaking-shoe E contains the sieves or screens and vibrates in 50 a plane parallel with the driving-shaft d, or in the longitudinal direction thereof.

F represents an eccentric mounted on the driving-shaft d, and F' is the eccentric strap or yoke provided on its upper side with a lug or ear f.

55

G represents an oscillating quadrant pivoted to a bifurcated bracket g, secured to the upper rear cross-piece of the frame A above the shaft d and swinging in the same plane as the shaking-shoe.

60

H is a metallic connecting-strap secured at its lower end to the lug f of the eccentric-yoke F' and at its upper end to a metallic plate I, secured to the bottom of the shaking-shoe by screws i. The plate I is provided on 65 its inner side with a projecting rim or lug i', which fits in a circular recess formed in the bottom of the shaking-shoe and assists in rigidly securing the plate to the shoe. The connecting-strap H passes over the curved 70 face of the quadrant G and is secured thereto by rivets or otherwise, so as to move therewith. The eccentric F imparts a reciprocating motion to the connecting-strap H, and the latter in turn transmits a similar movement to the shaking-shoe in the longitudinal direction of the driving-shaft d. The lower portion of the connecting-strap H adjacent to the lug f is preferably bent or 75 twisted in line with said lug, as shown, so that 80 the strap may yield laterally and follow the movements of the eccentric F without straining or bending the strap.

The connecting-strap consists of a single strip of metal having sufficient flexibility to 85 permit its being bent around the quadrant H, and is free from any joint, which are liable to become worn.

This construction forms a simple and cheap connecting device for transmitting motion to 90 the shaking-shoe directly from the driving-shaft. It does away with the usual counter-shaft, pulleys, and belt, and reciprocates the shoe with a less violent motion than the eccentric and connecting rod heretofore employed.

95 My improved device is shown as applied to the shaking-shoe of a grain-scourer; but it is obvious that it may be used in other similar machines in which the shaking-shoe is arranged above the driving-shaft.

I claim as my invention—

The combination, with the stationary supporting-frame and the horizontal driving-shaft journaled therein, of a shaking-shoe supported upon the main frame above the driving-shaft, an eccentric F, mounted on the driving-shaft and having a yoke provided with a lug f, an oscillating quadrant G, pivoted to the main frame above the driving-shaft, and a metallic connecting-strap H, running over said quadrant and secured with its

upper end to the shaking-shoe and having its lower end twisted in line with the lug f of the eccentric and secured to the same, substantially as set forth.

Witness my hand this 29th day of May, 1888. 15

WILLIAM W. HUNTLEY.
